(57) **CLAIM**

We claim the ornamental design for an adjustable convertible bicycle canopy, as shown and described.

DESCRIPTION

FIG. 1. is a front perspective view of our new and original ornamental design for an adjustable convertible bicycle canopy.

FIG. 2 is a right side elevation view thereof;

FIG. 3 is a top plan view thereof;

FIG. 4 is a bottom plan view thereof;

FIG. 5 is a left side, top, and front isometric view thereof;

FIG. 6 is a right side, bottom, and rear isometric view thereof;

FIG. 7 is left side, top and rear isometric view thereof;

FIG. 8 is a left side, bottom, and rear isometric view thereof;

FIG. 9 is a left side, bottom and front isometric view thereof; and,

FIG. 10 is a left side, top, and front isometric view thereof, wherein the adjustable convertible bicycle canopy is shown as used and installed on a bicycle.

The cross hatching in the drawings is representing the webbing material used in the canopy.

The broken line showing the bicycle in FIG. 10 is included for the purpose of illustrating environmental structure and forms no part of the claimed design.

1 Claim, 5 Drawing Sheets
